UNITED STATES PATENT OFFICE.

ERNST R. HOPPLER, OF LUCIVILLE, PENNSYLVANIA.

BUTTON.

No. 909,598.

Specification of Letters Patent.

Patented Jan. 12, 1909.

Application filed March 18, 1908. Serial No. 421,792.

To all whom it may concern:

Be it known that I, ERNST R. HOPPLER, a subject of the Emperor of Germany, residing at Luciville, in the county of Washington 5 and State of Pennsylvania, have invented certain new and useful Improvements in Buttons, of which the following is a specification, reference being had therein to the accompanying drawing.

10 This invention relates to buttons, commonly styled bachelor buttons, and the primary object of my invention is to provide a simple and inexpensive button that can be easily and quickly attached to a piece of 15 fabric.

A still further object of my invention is the provision of novel means for securing the head of a button to the shank and back thereof.

20 With the above and other objects in view, the invention consists in the novel construction, combination and arrangement of parts to be presently described and then specifically pointed out in the appended claim.

25 Referring to the drawing forming part of this specification, Figure 1 is a vertical sectional view of my button, partly in elevation. Fig. 2 is a plan of a plate used in connection with a button. Fig. 3 is a plan of a 30 cup shaped spring used in connection with the button, and Fig. 4 is a plan of a closure disk of the head of my button.

In the accompanying drawing, 1 designates a shank having a disk 2 constituting 35 the back of a button. The shank is provided with a truncated-cone shaped head 3.

The head of the button which is adapted to fit upon an object secured to the shank 1 comprises a disk 4 provided with a depending 40 annular flange 4^a, said flange being angle-shaped in cross section and which is adapted to support a plate 5 and a cup-shaped back 7, the latter being formed with a laterally extending marginal portion 7^a.

45 The marginal portion 7^a of the cup-shaped back 7 is interposed between the margin of the lower face of the plate 5 and the inwardly extending portion of the flange 4^a. From such an arrangement it is evident that

the depending flange 4^a couples the plate 5 and the back 7 to the disk 4. The plate 5 is provided approximately centrally thereof with a seat 6 for the reception of a head 3 of the shank 1 and the back 7 is also provided with an annular seat 7^b for a purpose to be 55 hereinafter referred to.

Interposed between the plate 5 and the back 7 is a cup-shaped member 9 having its top edge engaging the lower face of the plate 5 and its lower portion engaging the 60 seat 7^b. The cup-shaped member 9 is formed with a centrally disposed opening 10 and a plurality of radiating slits 11 which project from the said opening 10. The slits 11 provide the bottom of the member 9 with a 65 plurality of resilient gripping sections 12 adapted to engage and embrace the shank 1, thus preventing the head 3 of the shank 1 from being easily detached from the head of the button. 70

When the shank 1 is positioned, the free ends of the sections 12 will be elevated as clearly shown in Fig. 1. Such action places the sections 12 under tension and as they engage the shank 1, the latter will be held in 75 position. To facilitate the gripping of the shank 1 by the sections 12, the free ends of said sections are curved upon the arc of a circle.

The function of the plate 5 with the seat 80 6 is to prevent the shank 1 from wobbling when positioned in the head of the button.

Having now described my invention what I claim as new, is:—

In a button, the combination with a shank 85 having a button back and a truncated cone-shaped head, of a button head adapted to fit upon said shank, said head comprising a disk having a depending annular flange L-shaped in cross section, a plate arranged 90 against the disk and provided with a seat for the head of said shank, a cup-shaped back provided with a laterally extending marginal portion interposed between the margin of the plate and the inwardly extending portion of said flange whereby the plate and back are coupled with the disk, and a cup-shaped member interposed be- 95

tween said plate and back, said member at its lower end seating in said back and having its top edge engaging with the inner face of said plate, said member having a central opening and a plurality of slits extending from said opening, said slits providing a series of gripping sections adapted to embrace and engage said shank when the latter

is positioned in the head to prevent the separation of the shank from the head. 10

In testimony whereof I affix my signature in the presence of two witnesses.

ERNST R. HOPPLER.
